W. D. BURGIN.
ART OF FORMING CONCRETE WALLS.
APPLICATION FILED NOV. 4, 1918.

1,305,687.

Patented June 3, 1919.

UNITED STATES PATENT OFFICE.

WILLIAM D. BURGIN, OF JOPLIN, MISSOURI.

ART OF FORMING CONCRETE WALLS.

1,305,687.

Specification of Letters Patent. Patented June 3, 1919.

Application filed November 4, 1918. Serial No. 260,989.

To all whom it may concern:

Be it known that I, WILLIAM D. BURGIN, a citizen of the United States, residing at Joplin, in the county of Jasper and State of Missouri, have invented certain new and useful Improvements in the Art of Forming Concrete Walls, of which the following is a specification, reference being had to the accompanying drawings.

10 This invention relates to the art of building cement walls, and particularly to the manner of building a cement wall with an insulated space within the wall to prevent the wall from sweating.

15 The general object of the invention is to provide a method of and apparatus for building a wall of this character which is very easily applied and whereby a wall may be built both expeditiously and cheaply.

20 A further object is to provide for building a wall of this character in such manner that the space between the outer surfaces of the wall may be filled with slag or other granular material as the wall is built and before 25 the cement sets, this granular material in the insulating space permitting the form in which the cement is cast to be raised before the cement entirely sets.

25 A further object in this connection is to provide means whereby the granular material may be drawn away in case it be desired to leave the wall an air space.

Other objects will appear in the course of the following description.

35 My invention is illustrated in the accompanying drawings, wherein:—

Figure 1 is a horizontal sectional view of a wall constructed in accordance with my invention showing in plan the foundation upon which the wall rests;

Fig. 2 is a horizontal section on an enlarged scale;

Fig. 3 is a vertical transverse section through the wall;

45 Fig. 4 is a horizontal section showing the complete wall with tie bars used in place of studding and with the slag removed; and

Fig. 5 is a fragmentary top plan view of two coacting forms used in building a wall 50 without joists.

In Fig. 1, I illustrate a plan view partly in section of a portion of a wall constructed in accordance with my invention and in this figure, 10 designates the foundation of the wall, and 11 joists or like structural members disposed at intervals upon the founda-

tion. Assuming that the space between these joists is to be filled with concrete and that an interior insulating space is to be left within each concrete pier disposed between 60 the joists 11, then the procedure is as follows: Between each pair of joists are disposed the sheet iron forms 12 which are as long as the space between the joists. These forms are disposed between the joists so that 65 they are spaced from each other a distance equal to the width of the insulating space which is to be left within the walls and spreaders 14 are disposed between these forms 12 so as to separate the forms, these 70 spreaders being preferably integral with the forms. Form boards or like members 15 are disposed against the interior edges of the studding 11. Metallic slag or other granular material 16 is now filled into the space between the forms 12 up to the top of the forms and then concrete 17 in liquid, or semi-liquid form, is then poured or tamped 75 into the space between the form boards 15 and the forms 12.

As soon as the top of the forms 12 have been reached, that is, as soon as the top of the concrete is level with the top of the slag, the forms 12 are raised to the top of the concrete and the process repeated until the 85 top of the studding is reached or until the desired height is reached. This is done without waiting for the concrete to set, for the reason that the granulated slag will not unite with the concrete when the forms are raised, and later on this granular filling which, as before stated, is preferably metal slag, may be removed by means of an opening left at the bottom of the wall for this purpose. The metallic slag or other granular material may, however, be left in place, if so desired, and if so left in place this 90 granular material acts as a thoroughly good insulator.

The spreaders 14 may be attached to the 100 forms 12 or may be separate therefrom but preferably they will be attached thereto. In the event that studding is not used in the building then reinforcing members 18 should be disposed transversely at intervals across 105 the wall so as to connect the outer and inner concrete layers and bind the wall together. It is obvious, of course, that where window frames and door frames occur, that suitable forms will be used for the purpose of leaving these openings through the wall and that 110 forms 12 may be made in any desired shape

to secure a suitable contour or configuration to the wall. The sheet iron forms 12 are very light, may be easily shifted and may be used over and over again, as may the slag 5 which is withdrawn from between the forms 12 each time that the section of the wall has reached the proper height. Preferably the slag which I use is lead slag, but I do not wish to be limited to this particular form of 10 slag, nor to the use of slag as other granular substances might be used, though I find that slag is thoroughly effective and is cheap because it is otherwise a waste product.

Where a wall is to be built without studding, several metal forms may be placed along the foundation with the ends lapped an inch or so. These forms slightly differ from the forms shown in Figs. 1 and 2 in that one end of the form is approximately 20 one-fourth inch narrower than the other end of the form so that the narrow end of one form may be inserted in the large end of the other form. These forms are to be about three or four feet in length, but of 25 course may be of any desired size.

As before stated, there may be an opening left at the bottom of the wall for the purpose of removing the slag, as illustrated in Fig. 3 and in dotted lines in Fig. 2. In this 30 case a box 19 is disposed midway between the studding, this box having a top and two side walls. After the concrete hardens and the outside forms 15 are removed, the boxes 19 are removed and the space plugged with 35 a cement block. When studding is not used these boxes should be placed about three or four feet apart along the foundation.

The advantages of a wall constructed in accordance with my invention are that the 40 concrete does not extend from the outside surface to the inside surface of the wall and this prevents the conduction of heat, moisture or cold through the concrete. No skilled labor need be used in the construction of 45 the wall and it is obvious that the elements which go to form the wall are of the simplest character. No complicated or expensive air space forming device is necessary and it is not necessary to use wooden studding or any particular form of studding unless desired. I have found in actual practice 50 that walls may be very expeditiously made in accordance with the above description, that they are relatively cheap, and that if 55 the granulated slag is used as a filler be-

tween the outer and inner portions of the walls, the wall will be thoroughly insulated from the effects of cold, moisture or heat.

I claim:

1. The method of forming hollow concrete walls which consists in disposing a hollow, open-ended inner form within a hollow open-ended outer form, with the walls of both forms in vertical position, filling the space within the inner form with granular material through the uppermost open end of the inner form, filling the space between the outer and inner forms with concrete to a level with the upper surface of the granular material and then lifting the inner form 70 before the concrete is set to form a superposed section of wall, the granular material left between the outer and inner concrete portions of the wall acting as a core for the concrete. 75

2. The method of forming walls which consists in disposing a hollow open-ended inner form within a hollow open-ended outer form, with the walls of the forms in vertical position, filling the inner form through its 80 upper open end with granular material, filling the space between the inner and outer form with concrete, raising the inner form to a level with the top of the granular material, and repeating the steps above recited 85 to form a complete wall.

3. The method of forming hollow concrete walls which consists in disposing a hollow, open-ended inner form within a hollow open-ended outer form, with the walls of 90 both forms in vertical position, filling the space within the inner form with granular material through the uppermost open end of the inner form, filling the space between the outer and inner forms with concrete to 95 a level with the upper surface of the granular material and then lifting the inner form before the concrete is set to form a superposed section of wall, the granular material left between the outer and inner concrete 100 portions of the wall acting as a core for the concrete, and then removing the granular material to leave an air space.

In testimony whereof I hereunto affix my signature in the presence of two witnesses.

WILLIAM D. BURGIN.
